(57) **CLAIM**

The ornamental design for a pet house board, as shown and described.

DESCRIPTION

FIG. 1 is a perspective view of a pet house board showing my new design;
FIG. 2 is another perspective view thereof;
FIG. 3 is a front elevational view thereof;
FIG. 4 is a rear elevational view thereof;
FIG. 5 is a left side elevational view thereof;
FIG. 6 is a right side elevational view thereof;
FIG. 7 is a top plan view thereof;
FIG. 8 is a bottom plan view thereof; and,
FIG. 9 is a perspective view of the pet house board where the pet house board is in a configuration of use.
The long evenly-spaced broken lines in the drawings depict portions of the pet house board that form no part of the claimed design. The short evenly-spaced broken lines in the drawings depict stitching and form part of the claimed design.

1 Claim, 9 Drawing Sheets
